DESIGN FOR A BATHTUB

Walter J. Kohler, deceased, late of Kohler, Wis.,
by Herbert V. Kohler, John M. Kohler, and
Walter J. Kohler, Jr., executors, Kohler, Wis.

Application June 4, 1941, Serial No. 101,304

Term of patent 14 years

To all whom it may concern:

Be it known that Herbert V. Kohler, John M. Kohler, and Walter J. Kohler, Jr., citizens of the United States and residents of Kohler, in the county of Sheboygan and State of Wisconsin, executors of the last will and testament of Walter J. Kohler, late a citizen of the United States, have found that said Walter J. Kohler, deceased, had invented a new, original, and ornamental Design for Bath Tubs, of which the following is a specification, reference being had to the accompanying drawing, forming part thereof.

We claim:

The ornamental design for a bath tub, as shown.

HERBERT V. KOHLER,
JOHN M. KOHLER,
WALTER J. KOHLER, JR.,

Executors of the Last Will and Testament of Walter J. Kohler, Deceased.
